UNITED STATES PATENT OFFICE.

LEROY F. HARZA, OF CHICAGO, ILLINOIS.

HYDRAULIC TURBINE.

Application filed November 24, 1918. Serial No. 240,137.

To all whom it may concern:

Be it known that I, LEROY F. HARZA, a citizen of the United States, and resident of Chicago, in the county of Cook and State of Illinois, have invented a new and useful ⁵ Hydraulic Turbine, of which the following is a specification.

This invention relates to hydraulic turbines and relates particularly to axial flow ¹⁰ turbines.

The object of the present invention is to provide a hydraulic turbine of the general type specified of new and novel construction, whereby power plants embodying ¹⁵ hydromotive units—as hydro-electric generators—may be greatly simplified and the cost thereof correspondingly reduced. To this end, my invention consists in connecting the turbine runner or rotor and the casing ²⁰ of the turbine having the relation of a rim thereto directly to each other so that they will form a unitary structure, and in rotatably mounting the unit formed thereby between the adjacent ends of the penstock and ²⁵ draft tube, said turbine rim or casing forming, in effect, a rotatable section of the water trunk.

Another object of my invention is to combine a hydraulic turbine directly with an ³⁰ electric generator so that they will constitute a compact unit in which the rotor of the generator surrounds and is carried directly upon the periphery of the turbine.

My invention also comprises the various ³⁵ other features, combinations of features and details of construction hereinafter described and claimed.

In the accompanying drawings, in which my invention is fully illustrated,

Figure 1 is a transverse, vertical sectional view of a power house, showing the manner of installing a hydraulic turbine of my invention as preferably applied for driving an ⁴⁰ electrical generator.

Figure 2 is an enlarged sectional view of my improved turbine combined with an electrical generator, as shown in Fig. 1.

Figure 3 is a sectional view on the line 3—3 of Fig. 2; and

Figure 4 is a fragmentary view substantially similar to Fig. 2, illustrating modified means for applying the power developed by my improved turbine.

At the present time, water power is very ⁵⁵ largely applied by means of hydro-electric

generators—that is, electric generators driven by means of hydraulic turbines—and because of this very common and generally known and well understood use and application of hydromotive units, I have, for purposes of concrete illustration, shown a hydraulic turbine of my invention connected in a novel manner for driving an electrical generator, said turbine and generator together forming what is commonly known and referred to as a hydro-electric generator.

I desire it understood, however, that the application shown is illustrative only, and that I do not limit myself thereto or to any specific application as, so far as I am aware, ⁷⁰ hydromotive units of my invention admit of general application for all uses and purposes for which present hydromotive units are adapted.

Referring now to Figures 1 to 3 of the ⁷⁵ drawings, A designates, as a whole, the power house of a hydro-electric plant, comprising side walls A'; A² and a floor A⁴, all of which rest directly on bed rock, indicated at A⁴, a' the normal head water level, or water level above the dam, a³ the normal tail water level or level below the dam, a an assumed head water level at flood stage, and a² an assumed tail water level at flood stage.

As regards its usual features and excepting as hereinafter particularly pointed out and described, the power house A may be of any usual or approved construction and will be readily understood by persons familiar with such structures without a detailed description thereof.

My improved hydromotive unit, designated as a whole B, is of any practical axial flow type, the type being immaterial to my invention, and as shown comprises a rotor ⁹⁵ or runner resembling a ship's propeller, designated 1, and a rim or casing 2 connected directly to each other so as to form a unitary structure. A propeller type of runner I now define as any axial flow runner consisting for ¹⁰⁰ my use of three or more blades in approximately radial positions the maximum dimension of the runner between the extreme upstream and downstream points thereof, measured parallel with its axis of rotation, being less than the diameter of the runner. The propeller 1 and casing 2 will preferably be made of cast metal and will preferably be cast integral with each other, though my invention contemplates equally forming ¹⁰⁵ 110

them separate and rigidly connecting them by suitable means, as bolts, screws or the like.

In accordance with my invention, the hydromotive unit B is relatively mounted with small clearance between the adjacent ends of the penstock 3 and the draft tube 4, both of which are made of boiler plate, concrete, or other material, of suitable thickness to afford requisite strength and both of which taper towards said hydromotive unit, the penstock 3 being preferably built into the wall A of the power house and the draft tube 4 into the wall A thereof.

The manner of mounting said hydromotive unit B upon the penstock 3 and the draft tube 4 is as follows:—Secured to the ends of said penstock and draft tube and fitted thereto, respectively, so as to form tight joints therewith, are rings 5 and 6, which may conveniently be formed of cast metal, preferably cast steel, on which are bearings which co-operate with corresponding bearings on the rim 2 of the turbine. As shown, said hydromotive unit B is supported by means of ball bearings comprising ball races formed by "cone" members 7 formed on the turbine rim 2 and "cups" 8 slidably fitted to bearings 9 formed on the rings 5 and 6 secured to the ends of the penstock and draft tube so as to be movable endwise thereon towards and from the cones 7, thus providing for adjusting said ball bearings. Also, to provide for installing said hydromotive unit B and for removing the same in case of necessity, the bearings 9 are made sufficiently long to provide for retracting the ball bearing cups 8 beyond the lateral faces of said hydromotive unit. The bearing cups 8 are adapted to be adjusted lengthwise of the bearings 9 on the rings 5 and 6 towards and from the bearing cones 7 by bolts 10 secured in said bearing cups, threaded to which are nuts 11 rotatably mounted against endwise movement in brackets 12 secured to the rings 5 and 6 outside of said bearing cups, and said cups are adapted to be rigidly secured to said rings 5 and 6 in different adjusted positions. Within the contemplation of my invention, any desired or approved means may be employed for this purpose and it will not, therefore, be necessary either to show or describe the same in detail. As shown, the nuts 11 are held from endwise movement by means of circumferential grooves 15 formed in the surfaces thereof, which engage open sided slots formed in the brackets 12, the sides of said grooves embracing opposite sides of said brackets. For convenience in turning the adjusting nuts 11, hand wheels 17 are preferably secured thereto, said hand wheels and nuts being preferably formed integral with each other. Also, to provide for adjusting the bearing cups to

their bearings 9 on the rings 5 and 6, the brackets 12 are removably secured to said rings by screws or other suitable means.

In the operation of my improved turbine, the water passing through the turbine will exert a pressure on the turbine rotor 1 which will tend to force the face of the turbine casing 2 adjacent to the draft tube 4 against the face of the ring 6 opposed thereto. This pressure requires the use of a thrust bearing of any usual type, such as a babbitt disk, Kingsbury type, oil pressure or water pressure type, all of which are old and well known in many different applications. What I now consider to be the preferable type of thrust bearing for this purpose is the water pressure type wherein I provide an annular chamber 18 in the face of the turbine casing 2 opposed to the face of the ring 6 and connect said chamber with a source of supply of water under pressure, not shown, the relation being such that the aggregate pressure exerted by the water in said chamber 18 will slightly more than counterbalance the water pressure on the turbine rotor 1. Thus, the water pressure in the chamber 18 will tend to force the turbine casing away from the opposed face of the ring 6, but should any movement occur, it would open a slight space between the opposed faces of said casing and ring, which would permit sufficient leakage from said chamber into the water trunk to reduce the pressure in said chamber to exactly counterbalance the water pressure on the turbine rotor. This would be so for the reason that the pressure in the chamber 18 would be greater than the pressure in the water trunk.

Leakage from said chamber 18 outwardly can be reduced by suitable packing applied between the opposed surfaces of said turbine rim or casing 2 and ring 6 outside of said chamber 18. Suitable packing for this purpose can readily be devised and supplied by persons familiar with hydromotive construction without the exercise of invention and such packing is, therefore, neither shown nor described, as to do so would needlessly increase the length of the specification without in any way elucidating the invention.

In like manner, the space between the opposed faces of the turbine casing 2 and the ring 5 on the penstock is adapted to be packed or sealed by suitable packing means. Packing for this purpose can also readily be devised by skilled mechanics and is not, therefore, either shown or described. At both locations the pressure of packing required to entirely eliminate leakage, even if this were possible, would be objectionable because of the excessive friction produced and the consequent short life of the packing. However, as access of moisture to the electric generator would result in short-circuit-

ing the same and burning it out, where my improved turbine is applied for use in connection with an electrical generator, the rotor of which is mounted directly on the 5 turbine casing, as shown and presently described, means are provided for drawing off any water which may leak through the spaces between the faces of the turbine casing and the rings 5 and 6. As shown, said 10 means consists of interior grooves 19 formed around the bearing cups 8 in line with the spaces between the opposed faces of said turbine casing and the rings, said grooves being provided at their bottoms with suitable 15 drainage connections through which any water which may leak or be discharged into said grooves may drain off. In practice, however, I prefer to apply a continuous suction to the drainage connections of said 20 grooves. Simple means for this purpose consists in making pipe connections to the drainage openings of said grooves, as indicated at 20, and connecting said pipe connection with a vacuum pump or other suction 25 means, not shown, adapted to run continuously.

As shown, the opposed faces of the turbine casing and ring 5 are provided with a series of annular grooves 21 arranged to 30 form a series of chambers, which, as is well known, will retard the passage of water through said space, thereby accomplishing the same purpose as packing and without mechanical friction.

35 As applied in use as part of a hydro-electric generator, I preferably mount the rotor of the electrical generator directly upon the turbine rim 2, the stator of the electrical generator being supported on a suitable base 40 so as to surround the rotor thereof mounted on the turbine rim, as aforesaid.

This application of my improved turbine is illustrated in Figures 1 to 3 of the drawings, in which 22 designates the poles of the 45 rotor of the electrical generator mounted directly upon the rim of the turbine, and 23 the stator of said generator which surrounds said rotor. As regards their general construction—both mechanical and electrical—50 the stator and rotor of said electrical generator may be of any desired or approved construction and will be readily understood from the drawings by persons familiar therewith without a description thereof in 55 detail. For this reason, said rotor and stator are indicated diagrammatically only.

In order that the stator of the electrical generator shall not interfere with the installation of the hydromotive unit B and its removal when desired, the supporting lugs 24 60 of the stator which bolt to the base 25 on which said stator is supported, are slidably mounted on the base as customary in all standard horizontal shaft generators.

65 When installing a hydraulic turbine of my

invention, great care must be exercised in setting the penstock and draft tube in order that the bearings for mounting the rim of said turbine thereon shall register with each other, as otherwise it would be impossible 70 to assemble the bearings which support the turbine. In practice, this can be effected by securing said penstock and draft tube in position with the bearing rings which support the bearings for the turbine rim or 75 casing secured thereto, and in rigidly connecting the adjacent ends of said penstock and draft tube with the bearings thereon in axial alignment with each other, and in then pouring the concrete forming the settings 80 for said penstock and draft tube, all of which is old practice. When said concrete hardens, the connection between the ends of said penstock and draft tube may be detached. In this manner, alignment of the 85 turbine bearings will be assured and the convenient installation of the turbine provided for.

Preferably, also, the adjacent ends of said penstock and draft tube are additionally supported by and rigidly secured to what may be described as saddles formed on a supporting base secured to the floor A³ of the power house or other support. In a hydro-electric generator, said saddles, indicated at 26, are formed directly on the stator base 25, being preferably formed integral with the stator base in such position that the remote end of the rings 5 and 6 will rest therein, respectively, and said saddles being 100 bolted or otherwise detachably secured to said rings.

As applied for use as part of a hydro-electric generator, my improved hydraulic turbine has several very great advantages, 105 among which may be enumerated the following:—

1. Straight line flow of water until expansion in draft tube is complete and consequently greater efficiency.
2. Avoids mounting heavy machinery on arches or floors over water passages, penstocks and draft tubes.
3. Avoids deep excavation in coffer dam for draft tubes; and
4. Reduces the required width of power house building.

For general use, either for driving an electrical generator or other machine, instead of mounting the rotor of the driven machine 120 directly upon the rotor of the turbine, as shown in Figures 1 to 3, and heretofore described, I contemplate the use of a gear, a sprocket wheel or a pulley—either for a belt, chain or a rope drive—on said rotor. 125

This modification of my invention is shown in Figure 4 of the drawings, in which B' designates the turbine, mounted between the adjacent ends of the penstock 3' and the draft tube 4', and which, as regards its gen- 130

eral construction, may be substantially identical with the turbine B (Figures 1 to 3). The generator or other machine to be driven by said turbine is operatively connected with said turbine by means of a belt, chain-belt, gear or the like, indicated at C, on the casing of the turbine and preferably formed integral therewith, comprising a rim 27 and a web or spokes 28, which connect said rim

10 with the casing of the turbine.

In some instances, the water power may be best utilized by constructing the penstock and the draft tube so that their longitudinal axis is inclined instead of horizontal, as shown, thus facilitating the gravity flow of the water therethrough and requiring a smaller total angular change in direction from head water to tail water. In such instances, the turbine will be disposed in an

15 incline to the horizontal, with its axis of rotation coincident with the longitudinal axis of the penstock and draft tube.

While I consider a turbine of the propeller type, such as herein shown and defined, as being preferable for the carrying out of my invention, I do not desire or intend to limit myself thereto, as it is possible and even probable that other types of axial flow turbines may be used with good results.

30 I claim:

1. A hydromotive unit comprising an axial flow rotor and a rim or casing secured thereto so as to rotate therewith; constructed and arranged to be rotatably mounted with clearance between the adjacent ends of the penstock and draft tube, and means for disposing of the leakage between fixed and revolving parts, substantially as described.

2. A hydromotive unit comprising an axial flow rotor and a rim or casing secured thereto so as to rotate therewith, constructed and arranged to be rotatably mounted between the adjacent ends of the penstock and draft tube, and means for disposing of the leakage between fixed and revolving parts, and means for applying power developed thereby directly from the rim of said rotor, substantially as described.

3. A hydromotive unit comprising an axial flow rotor and a rim or casing secured thereto so as to rotate therewith, constructed and arranged to be rotatably mounted between the adjacent ends of the penstock and draft tube, and means for disposing of the leakage between fixed and revolving parts and with electrical generator built circumferentially therewith, the poles thereof mounted on the rim of said hydromotive unit, substantially as described.

4. A hydromotive unit comprising an axial flow rotor of the propeller type and a rim or casing secured thereto so as to rotate therewith, constructed and arranged to be rotatably mounted between the adjacent

65 ends of the penstock and draft tube, and means for disposing of the leakage between fixed and revolving parts, substantially as described.

5. A hydromotive unit comprising an axial flow rotor of the propeller type and a rim or casing secured thereto so as to rotate therewith, constructed and arranged to be rotatably mounted between the adjacent ends of the penstock and draft tube and means for disposing of the leakage between

70 fixed and revolving parts, and means for applying power developed thereby, substantially as described.

6. A hydromotive unit comprising an axial flow rotor of the propeller type and a rim or casing secured thereto so as to rotate therewith, constructed and arranged to be rotatably mounted between the adjacent ends of the penstock and draft tube, and means for disposing of the leakage between

75 fixed parts and revolving parts, and with electrical generator built circumferentially therewith, the poles thereof mounted on the rim of said hydromotive unit.

7. The combination of a penstock, a draft tube, and a hydromotive unit of the type specified rotatably mounted between said penstock and draft tube, with means for disposing of the leakage between fixed and revolving parts, the bearings for rotatably mounting said hydromotive unit being constructed and arranged to permit the installation and removal of said hydromotive unit, substantially as described.

8. The combination of a penstock, a draft tube, and a hydromotive unit of the type specified rotatably mounted between said penstock and draft tube, with means for disposing of the leakage between fixed and revolving parts, the bearings for said hydromotive unit comprising movably supported members retraction of which will disengage said hydromotive unit from said penstock and draft tube, substantially as described.

9. The combination of a penstock, a draft tube, and a hydromotive unit of the type specified rotatably mounted between said penstock and draft tube, the bearings for said hydromotive unit comprising bearing members slidably mounted on said penstock and draft tube and movable towards and from said hydromotive unit to engage the same with and disengage it from said penstock and draft tube, substantially as described.

10. The combination of a penstock, a draft tube, and a hydromotive unit of the type specified rotatably mounted between said penstock and draft tube, the bearings for mounting said hydromotive unit comprising bearings formed on the penstock and draft tube and on the rim or casing of said hydromotive unit, substantially as described.

11. The combination of a penstock, a draft tube, and a hydromotive unit of the type

120

125

130

specified rotatably mounted between said penstock and draft tube, with means for disposing of the leakage between fixed and revolving parts, the bearings for mounting 5 said hydromotive unit comprising a movable member or members, substantially as described.

12. The combination of a penstock, a draft tube, and a hydromotive unit of the type 10 specified, and means for rotatably mounting said hydromotive unit between said penstock and draft tube, comprising rings on said penstock and draft tube, bearing members slidably mounted on said rings and bearings on 15 the rim or casing of said hydromotive unit which co-operate with the bearings on said bearing members, substantially as described.

13. The combination of a penstock, a draft tube, and a hydromotive unit of the type 20 specified rotatably mounted between said penstock and draft tube, the rim or casing of said hydromotive unit and draft tube being provided with opposed surfaces, one 25 of said surfaces being provided with a chamber adapted to be connected with a source of liquid under pressure to counter-balance the water pressure on the rotor of the hydromotive unit, substantially as described.

14. The combination of a penstock, a draft tube, and a hydromotive unit of the type 30 specified rotatably mounted between said penstock and draft tube, and means for draining off water which leaks through between said penstock and draft tube and the casing of said hydromotive unit, substantially as described.

15. The combination of a penstock, a draft tube, and a hydromotive unit of the type 40 specified rotatably mounted between said penstock and draft tube, and means for draining off water which leaks through between said penstock and draft tube and the casing of said hydromotive unit, said means 45 comprising flanges on said penstock and draft tube provided with internal grooves positioned opposite the points of leakage, and drainage connections to the bottoms of said drainage grooves, substantially as described.

16. The combination of a penstock, a draft tube, and a hydromotive unit of the type 50 specified rotatably mounted between said penstock and draft tube, and means for draining off water which leaks through between said penstock and draft tube and the casing of said hydromotive unit, said means 55 comprising flanges on said penstock and draft tube provided with internal grooves positioned opposite the points of leakage, and means applied to the bottoms of said 60 grooves for exerting a continuous suction thereto, substantially as described.

17. The combination of a penstock, a 65 draft tube, and a hydromotive unit of the

type specified rotatably mounted between said penstock and draft tube by means of ball bearings comprising movably supported members slidably mounted on the penstock and draft tube, substantially as described. 70

18. The combination of a penstock, a draft tube, and a hydromotive unit of the type 75 specified rotatably mounted between said penstock and draft tube by means of ball bearings comprising cones on the rim or casing of the hydromotive unit and cups slidably mounted on the penstock and draft tube, substantially as described.

19. The combination of a penstock, a draft tube, means for supporting the same, 80 comprising means for rigidly connecting the adjacent ends thereof, and a hydromotive unit of the type specified rotatably mounted between said penstock and draft tube and means for disposing of the leakage between 85 fixed and revolving parts, substantially as described.

20. The combination of a penstock, a draft tube, means for supporting the same, comprising a base and saddles thereon in 90 which said penstock and draft tube are secured, and a hydromotive unit of the type specified rotatably mounted between said penstock and draft tube, with means for disposing of the leakage between said hydromotive unit and said penstock and draft tube, substantially as described. 95

21. A hydromotive unit comprising a hydraulic turbine of the propeller type and power transmitting means mounted upon the periphery thereof to rotate therewith between the fixed ends of penstock and draft tube, and means for draining away the leakage between fixed and revolving parts. 100

22. A hydromotive unit comprising a hydraulic turbine of the propeller type, and an electric generator, the rotor of which is mounted upon the perimeter of said turbine designed to rotate between the fixed ends of penstock and draft tube and means for draining away the leakage between 105 fixed and revolving parts. 110

23. The combination of a hydraulic turbine of the propeller type, and an electric generator concentrically mounted with their transverse axes disposed in a common plane, with fixed penstock and draft tube leading the water respectively to and from the turbine and means for draining away 115 the leakage between fixed and revolving parts. 120

24. The combination of a hydraulic turbine of the propeller type, and an electric generator mounted concentrically with and surrounding said turbine, the rotor of said generator being fixedly connected to and carried by the runner of said turbine, with fixed penstock and draft tube leading the water respectively to and from the turbine and means for draining away the leakage 125 between fixed and revolving parts. 130

25. The combination of a hydraulic turbine of the propeller type comprising a runner provided with a circumferential rim forming a portion of the water conduit to 5 and from the turbine and means for disposing of the leakage between the revolving turbine rim and the fixed ends of the water conduit, and an electric generator surrounding said runner and having the generator 10 poles fixedly mounted upon said runner rim.
26. An axial flow hydraulic turbine with circumferential band or rim forming part of the water conduit and a penstock leading 15 the water thereto and a draft tube therefrom, between the fixed ends of which the rim of the turbine revolves with clearance, and a water lubricated thrust bearing on the fixed end of the draft tube against 20 which the turbine rim revolves.
27. An axial flow hydraulic turbine with circumferential band or rim forming part of the water conduit and a penstock leading 25 the water thereto and a draft tube therefrom, between the fixed ends of which the rim of the turbine revolves with clearance, and a water lubricated thrust bearing on the fixed end of the draft tube against which 30 the turbine rim revolves, with means for disposing of the leakage between said turbine and said penstock and draft tube.
28. An axial flow hydraulic turbine with circumferential band or rim forming part of the water conduit and a penstock leading 35 the water thereto and a draft tube therefrom, between the fixed ends of which the rim of the turbine revolves with clearance, and a water lubricated thrust bearing on the fixed end of the draft tube against which the turbine rim revolves, with 40 means for disposing of the leakage between said turbine and said penstock and draft tube, with power transmitting means mounted on said rim.
29. An axial flow hydraulic turbine with 45 circumferential band or rim forming part of the water conduit and a penstock leading the water thereto and a draft tube therefrom, between the fixed ends of which the rim of the turbine revolves with clearance, 50 and a water lubricated thrust bearing on the fixed end of the draft tube against which the turbine rim revolves, with means for disposing of the leakage between said turbine and said penstock and draft tube and 55 with an electrical generator built concentrically therewith, the poles mounted upon said turbine rim.

In testimony that I claim the foregoing as my invention, I affix my signature this 20th day of November, 1919.

LEROY F. HARZA.
